(57) **CLAIM**

The ornamental design for a window in a wall mounted dispenser cabinet, as shown and described.

DESCRIPTION

FIG. 1 is a perspective view of a window in a wall mounted dispenser cabinet showing our new design; and, FIG. 2 is a front elevational thereof.

The broken line showing of a wall mounted dispenser cabinet is included for the purpose of illustrating portions of the article and forms no part of the claimed design.

1 Claim, 2 Drawing Sheets
